TOBACCO PIPE

Albert Backus, San Francisco, Calif.

Application June 27, 1938, Serial No. 215,969

1 Claim. (Cl. 131—218)

My invention relates to new and novel improvements in the bore of the bowl of smoking-tobacco pipes to burn the tobacco without suppressing combustion and in co-operation therewith to provide a new and novel compact superior cooler for the smoke to pass through within a middle section of the stem, to provide highly improved results; and the objects of my invention are, first, to provide for improved combustion by changing old features that cause a suppression of combustion resulting in dampness and smoldering and in the formation of poisonous carbon monoxide and oxides of nitrogen in the lower half of the tobacco receptacle where the capacity for tobacco is usually large or the means for supply of oxygen for proper combustion are too limited, said improved combustion is attained by means of a conical bore in the lower half of the tobacco receptacle having the shape of an inverted conical frustum to reduce the tobacco load and to cause a contraction of the smoke and an increase in the supply of oxygen by means of improved draft in the lower half of said receptacle in order to supply an adequate amount of oxygen to support combustion to the degree required to burn the tobacco without smoldering clear down to the reduced bottom of the tobacco receptacle by means of a plurality of slots in said bottom forming a grill-shaped opening to communicate with a smoke passage in the stem directly under the tobacco receptacle; second, to guard against deleterious smoke caused by expansion of smoke in both the hot lower part of the bowl and the hot part of the stem and to aid in the prevention of toxic results from the nicotine and other chemicals in the tobacco as well as numerous chemicals in the air that are drawn through the fire in the tobacco receptacle including a varying high percentage of water vapor and varying small amounts of carbon dioxide, ammonia, nitric and sulphuric acids which, in a smoldering fire, produce pyridine and other harmful substances and toxins in the smoke; third, to separate the smoke-cooling section of the stem from the heat of the bowl by providing a comparatively short stem slightly increased in thickness to serve as a divide and as a nonconductor of heat between the bowl and the cooling section of the stem which is frictionally connected with the integral stem to the bowl, said cooling section consists of a casing having a comparatively long cylindrical bore and a short bit formed integrally with said casing to complete the entire stem of the pipe, said casing being provided with a solid cylindrical core divided into two connected sections separated by

5 an annular recess to serve as a trap for moisture and to retain solid matter, each section having a continuous longitudinally inclined helical groove with reverse U turns adjacent each end of each section, whereby said groove alternately reverses and parallels each preceding groove causing the smoke to travel longitudinally in a spiral practically from end to end of each section of said core many times its length to cool the smoke gradually and sectionally with very little expansion of smoke to cause excessive moisture, all of 10 which is provided in said casing requiring a bore approximately the size and length of a cigarette to accommodate five parallel grooves, in two of 15 which the smoke travels toward the bowl and in three toward the bit which together with the enclosure of the casing forms a long, continuous, circuitous duct in each of said sections, without increasing the prevailing length of the pipe and 20 with only a slight change in the prevailing popular shape of the combined parts forming the entire stem of the pipe; fourth, to provide a sectional supercooling core without any hole in it to complicate manufacture and cleaning, in combination with a cylindrical casing with a bit formed integrally therewith which may be easily molded and assembled and which is also adapted to be used in other pipes or in a cigarette holder; the 25 said core, bit and casing being preferably molded of hard rubber; said core may also be made of any other durable material or it may be very cheaply made of absorbent material to be discarded when saturated; and fifth, to provide a bore in the bowl that is also adaptable for holding a tobacco cartridge to contact only a small part of the wall of the lower portion of the tobacco receptacle and to provide an open space between the rest of the wall of said receptacle and the fire therein. 30 The ultimate objective being to solve a scientific chemical problem by providing a compact pipe, simple and practical to manufacture, that will properly burn tobacco and cool the smoke so as to retain the pleasant nicotianin aromatic odor and the essential oily and resinous flavor of the 35 smoke free from poisonous gaseous products.

40 I attain these objectives by means of a complete plan that includes all of the parts and combination of parts that relate to the burning of the tobacco and handling the smoke as it passes through the bowl and the entire stem which is 45 illustrated in the accompanying drawing, in which—

50 Figure 1 is a longitudinal cross section of my 55 tobacco pipe showing the improved tobacco receptacle and the short bit 10 formed integrally

with the cylindrical casing 9 which encloses the cooling core B, together with the embodiment of the preferred form of my invention.

Figure 2 is a sectional view through the bowl as indicated by the line 2—2 of Figure 1.

Figure 3 is a sectional view taken on the line 3—3 of Fig. 1.

Figure 4 is a sectional view taken on line 4—4 of Fig. 1.

Figure 5 is a longitudinal sectional view of a modified form of the cylindrical casing 9 enclosing cooling core B where said cooling core is formed integrally with the bit 10 and frictionally connected with said casing. This form of bit, core and cylindrical casing is interchangeable with the form shown in Fig. 1 and may also be used as a cigarette holder.

Figure 6 is a general diagrammatic illustration of the smoke path throughout the length of the cooling core.

Referring more particularly to the drawing wherein like characters of reference designate corresponding parts, the bowl 1 is formed with a straight bore 2 to substantially one-half of its depth and terminates in a tapered bore 3 which extends downwardly to the reduced bottom 4 of the tobacco receptacle A. The bottom 4 is nearly flat and is slotted to form a grill-shaped opening 5 substantially as shown in Fig. 2 to communicate with passage 7. Directly beneath the grill 5 and extending longitudinally and co-axially with the stem 6 is a smoke passage 7 formed in the stem 6 with an increased diameter in the end to provide a chamber 8 adapted to receive the tubular extension of the cylindrical casing 9 which is formed integrally with the short bit 10. The preferable material for the bowl and its integral stem being bruyère but other suitable material may be used.

The casing 9 is formed with a centrally disposed cylindrical chamber 11 communicating with the conventional bore and slotted opening 12 of the bit 10. Thus a continuous smoke passage is provided from the tobacco receptacle A, through the grill 5, the smoke passage 7, the cylindrical chamber 8, the annular recess 15, the cylindrical chamber 11 through the circuitous groove 19 and through the bore and slotted passage 12 in bit 10.

A solid cylindrical cooling core B, preferably of uniform diameter, formed in two sections 13 and 14, separated by an annular recess 15, is adapted to fit snugly within the cylindrical chamber 11 and extends substantially the entire length thereof. The five parallel longitudinally inclined grooves 16 are formed in the surface of each of the core sections 13 and 14 and are helically disposed thereon with reverse turns forming a continuous duct through each section. The forward end of one groove 16 extends to the end of core section 13 nearest the smoke passage 7 and communicates with chamber 8 as at 17 while the opposite end of another groove 16 communicates with the annular recess 15 at 18. The grooves 16 are otherwise alternately connected together by two reverse bends in said grooves adjacent each end of the core section 13 as shown at 19 and illustrated in Figure 6, to form one continuous groove, reversing twice, between the points 17 and 18 which, with the surface of chamber 11, forms a continuous smoke passage nearly five times the length of cooling core 13. Similarly, the grooves 16 are formed and connected by reverse turns on the core section 14 to form a continuous, circuitous smoke passage from the an-

nular recess 15 at 20 to the end of the bore and slotted passage 12 at 21.

A diagrammatic illustration of the helical smoke passage with reverse turns formed on the core sections 13 and 14 is substantially shown in Figure 6.

The core sections 13 and 14 are shown of unequal length, it being advisable to have the longer section 13 nearest to the bowl to provide a sufficient length of smoke passage in front of the annular recess 15 to hold the major condensation of moisture from the air and the tobacco that mixes with the smoke. The annular recess 15 serves as a trap for said moisture as the smoke passes between the points 18 and 20.

The forward end of core B is formed with a button 22 to facilitate the removal of said core from chamber 11 for cleaning.

In Figure 5, the bit 10 is shown integrally formed with the cooling core B while the cylindrical casing 9 is separately formed and is adapted to fit snugly around the core B and against a shoulder 23 formed on the bit 10. In this instance the cooling core B is removed from the chamber 11 by pulling out the bit 10.

Something similar to a twist drill bit may be used to clean the small bore in the integral stem of the bowl to remove "caking," caused from heat, without forcing sediment into the grill. This bore seldom requires cleaning.

The pipe illustrated in the drawing shows the core of the size and length of a cigarette which is adequate for proper cooling. This size of core accommodates five parallel grooves of the proper size for smoke passage. A core with three grooves and one reverse bend at each end may be used if a smaller stem is desired with a shorter circuitous smoke passage.

There are two distinct types of old pipe bowls each having a uniformly large bore in which to burn tobacco; one has a side entrance from a stepped bore in the integral stem into the fireplace, to which type I make no claim whatever. The other has a downward communication to a large chamber beneath the bottom of the tobacco receptacle. This latter type, which I am not claiming broadly, but to which I have directed my new improvements, provides a measure of improved combustion due to downward drainage, but fails to eliminate carbon monoxide, fails to provide an adequate free draft, fails to eliminate the large, hot expansion chamber directly beneath the bottom of the tobacco receptacle, fails to eliminate metal tubes and metal cooling elements in the integral stem of the bowl and fails to provide adequate cooling means in the bit section of the stem to counteract the added heat caused from improved combustion.

To overcome such objectionable features I have based my new improvements on the results of certain basic experiments, as follows:

That a uniformly large bore in the bowl suppresses combustion in its lower half causing a "wet heel" and carbon monoxide in the smoke—a product of incomplete combustion which combines with the hemoglobin of the blood, expelling oxygen.

That a frusto-conical bore in the lower half of the tobacco receptacle with a grate-shaped opening through the reduced bottom, improves combustion to the degree attained in open-air burning of cigars and cigarettes where oxygen can freely support combustion.

That improved combustion increases heat in a pipe which requires superior cooling means,

That metal in the hot part of the stem intensifies heat and has a deleterious effect on the smoke,

That smoke cannot be cooled in a hot or warm part of the stem at or near the hot bowl,

That a large bore or chamber in a part of or through the entire integral stem of the bowl, as in the old pipes, releases large deposits of hot nicotine and other poisonous products in the hot section of said stem causing foul aqueous vapors and excessive moisture, that do not occur in a constricted bore in said position, and

That a reversal of the unitary plan of a pipe, completely changing the position of the cooling chamber, radically enlarged and re-shaped, and placing it entirely into the cool detachable stem section, is based on the proven fact that cool nicotine deposits do not emit foul odors, as is the result when allowed to accumulate in a hot chamber near the bowl.

I do not claim broadly, the old bit section of the stem having a marked taper that allows only a short, moderately enlarged bore in the end that is

5 detachably connected with the integral stem of the bowl, nor the old large bore in the upper half of the tobacco receptacle, nor the small, old bore in any part of the stem when used as a side entrance to the tobacco receptacle.

10 All other parts described herein are claimed as newly constructed or so radically enlarged and re-shaped and positioned or radiacally reduced and positioned or radically reconstructed as to constitute new parts for the purpose of improving the final result, in a new complete combination, each part designed to accomplish its individual purpose at a place where such function is necessary.

15 I claim:

A solid cylindrical core to fit snugly and slidably into a cylindrical casing, said core having a continuously advancing and reversing spiral groove in the surface of said core to carry smoke back and forth in spiral paths along the periphery of said core, all substantially as set forth.

ALBERT BACKUS.
